(57) **CLAIM**

The ornamental design for a liquid-evaporate delivery device, as shown and described.

DESCRIPTION

FIG. 1 is a perspective view of a liquid-evaporate delivery device;

FIG. 2 is a front view of the embodiment of FIG. 1.

FIG. 3 is a rear view of the embodiment of FIG. 1.

FIG. 4 is a right side view of the embodiment of FIG. 1.

FIG. 5 is a left side view of the embodiment of FIG. 1.

FIG. 6 is a top view of the embodiment of FIG. 1; and,

FIG. 7 is a bottom view of the embodiment of FIG. 1.

The broken lines are provided for illustrative purposes only and form no part of the claimed design.

1 Claim, 7 Drawing Sheets
